United States Patent Office

Des. 189,570
Patented Jan. 10, 1961

189,570

TELEPHONE BOOTH

Francis F. Peabody, Minneapolis, Minn.

Filed May 18, 1959, Ser. No. 55,937

Term of patent 14 years

(Cl. D13—1)

Fig. 1.

Fig. 4.

Fig. 2.

Fig. 3.

Fig. 1 is a front perspective view of a telephone booth showing my design;

Fig. 2 is a front elevational view;

Fig. 3 is a rear elevational view; and

Fig. 4 is a side elevational view thereof.

I claim:

The ornamental design for a telephone booth, as shown.
